UNITED STATES PATENT OFFICE.

DAVID W. BARROW, OF CHATTANOOGA, TENNESSEE.

CARD-DISPLAYING APPARATUS.

1,140,348.

Specification of Letters Patent. Patented May 25, 1915.

Application filed July 22, 1914. Serial No. 852,505.

To all whom it may concern:

Be it known that I, DAVID W. BARROW, a citizen of the United States, residing at Chattanooga, in the county of Hamilton 5 and State of Tennessee, have invented new and useful Improvements in Card-Displaying Apparatus, of which the following is a specification.

My invention relates to a card displaying 10 apparatus and has as its principal object the provision of automatic means whereby a plurality of cards may be automatically displayed in turn in a manner to attract the attention of passersby.

15 A second object of my invention is to provide a simple and efficient mechanism for producing an effective advertising display.

A final object of my invention resides in 20 the particular arrangement and combination 20 of parts hereinafter described.

In the accompanying drawings:—Figure 1 is a front elevational view of my apparatus. Fig. 2 is a side elevation of Fig. 1. Fig. 3 is a sectional view on the line A—A 25 25 of Fig. 2. Fig. 4 is a view similar to Fig. 3 but on an enlarged scale, the central portion of the apparatus being broken away. Figs. 5 and 6 are detail views of the escapement members shown in dotted lines in Fig. 4.

30 Referring more particularly to the drawings, 1 is a casing having two window apertures such as 2—2 in vertical alinement. Within the casing 1 is a number of cards such as 3 which have thereon pictures of 35 matter to be displayed, such as articles of merchandise or manufacturing processes. Each of the cards 3 has fixed along one edge thereof a rod such as 4 which, it will be understood, is of somewhat greater length 40 than the cards so that it projects at each end and thus can engage in the slots 5—6 which I provide in the sideboards 7—7 indicated in dotted lines in Fig. 1, and of which there are two mounted within the casing 1.

45 The slots 5 slope from the rear of the casing 1 toward the front and the slots 6 slope from the front of the casing toward the rear, and it will be understood that the front one of the cards 3, which are suspended from the upper pairs of slots 5, is visible through the top window 2, whereas the front one of the cards suspended from the slots 6 is visible from the lower window. 50 The front ends of the slots 5 and 6 are connected by vertical channels 7' formed by

metal strips such as 8 and it will be understood that if the rods or bars 4 are allowed to slide forwardly along slots 5 the front cards will drop down along the channels 7' and be guided into the slots 6 by means of 60 the lower ends 9 of the strips 8. It will be seen, moreover, that I provide a metal angle 10 on the opposite side of the channels 7 from the member 8, and just above the slots 6, the angle 10 sloping downwardly toward the 65 channel 7 and the end of the slots 6 so as to prevent any cards from falling backward into the casing.

The rods 4 are normally kept from sliding along the slots 5 and 6 by means of two 70 pairs of escapement members such as 11 and 12, respectively, the members 11 being placed at the lower ends of the slots 5 and the members 12 being placed at the lower ends of the slots 6. It will be noticed that the member 75 11 illustrated in detail in Fig. 5 has an irregular shaped slot cut through one face thereof, this slot opening on the right hand face of the member so as to form a vertical shoulder 13, and opposite the shoulder 13 80 the slot is cut away so that the ends of the front bar rest against this shoulder as indicated in Fig. 4. Above the shoulder 13 is a sloping face 14 which is inclined downwardly so as to form a point 15 on the opposite side of the slot front and at a level 85 slightly above the upper end of the shoulder 13. The slot in the face of the member 11 passes between the upper end of the shoulder 13 at the point 15 and thereupon broadens 90 out in a substantially horizontal direction. It will be seen that the slot is not only oblique to the block as a whole, but it also is angular in that it makes a sharp bend. 95 It will be obvious that the rods 4 will be held from moving along the slots 5 so long as the members 11 remain in the position shown in dotted lines in Fig. 4. When, however, the members 11 are moved downwardly, the point 15 will pass down so as to enter between the last one of the members 4 in the row and the next to the last, thus holding the next to the last one of the rods in position, as well as those behind it. The last 100 rod, however, will be released from the shoulder 13 and at the same time given a push by the sloping wall 14 so that it will slide along the slots and into the passage 7'. It then drops down into the slot 105 110 6 so as to be visible to the lower one of the

windows instead of the top one as previous. Upon the lifting of the member 11 the rods 4 slide along until the front one again rests against the shoulder 13. It will be obvious that the same operation will be gone through with by the rods and cards in the lower series whenever the escapement members 12 are lifted, the members 12 having shoulders 13', walls 14' and points 15' whose functions are identical with those of the correspondingly numbered parts of the members 11. It will be obvious, moreover, that a rod escaping from the slot 6 will rest upon the holding plates 16 which are so placed as to extend rearwardly from the lower ends of the slots 6 and which have a slight upward inclination.

I provide a means for elevating the individual cards from the plates 16 and introducing them again into the slots 5. This means comprises an elevator having chains or belts such as 17 which run over upper and lower pairs of rollers such as 18 and 19, respectively, and the chains or belts 17 carry fingers such as 20 which travel upward along the rear edge of the plate 7 between the plates 16 and pick the rods 4 from the plates 16 and carry them upwardly. In their upward path the rods 4 come into contact with a pivoted arm 21 which extends diagonally across the path of the rods near the upper ends of the slots 5. The rod 21 is pivoted at 22 and a spring 23 is provided which forces the arm 21 in a clockwise direction around the edges of the shaft 22.

As one of the rods 4 strikes the arm 21, it lifts the arm somewhat and is itself drawn away from the finger 20 by the arm and placed against the rear edge of the plate 7 so that when the rod reaches the end of the slot it readily slips into the same. Carried by the shaft 22 and the rod 21 is a normally horizontal lever 24.

The elevator chains 17 are driven by a motor such as 31, preferably of the electric type, by means of belts, one of which is designated as 32 and drives the pulley 33 from the motor pulley 34, while the second belt 35 drives the pulley 36 from the pulley 37, the last named pulley being on the same shaft as the pulley 33. The pulley 36 is on the same shaft as the top pair of wheels 18 of the conveyer 17. I employ a tension spring 28, shown in Fig. 2, to keep the elevator belt 17 from running slack. The lower end of the spring 28 is connected to a hook 29, the hook being threaded and run through a nut 30 fixed to the frame. The upper end of the spring 28 is shown as integral with a hook 41 which engages the shaft of the wheels 19 of the elevator.

It will be understood that I do not limit myself to the arrangement shown and described for accomplishing the objects of my invention, but contemplate all modifications

of my invention as are mechanically equivalent to the embodiment shown and described therein.

Having thus described my invention, what I claim is:—

1. A card displaying apparatus comprising in combination, a casing arranged to hold a plurality of cards and having at least one aperture therein for the display of cards, a pair of guides sloping downwardly from the rear to the front of said casing in such position as to hold the cards in the guides in front of the aperture, a second pair of guides in said casing below the display aperture and inclined downwardly from the rear, means for elevating cards from the lower guides to the upper guides, and escapement means for controlling the exit of cards from said top and bottom guides, said escapement means comprising escapement blocks having oblique slots therethrough for holding the cards or permitting the same to pass along the guides according to the position of the blocks, and means whereby the escapement blocks may be operated to permit the passage of cards at intervals. 70 75 80 85 90

2. In a device of the class described, an escapement mechanism comprising a block having an angular slot therethrough, and automatic means for operating said block 95 to permit the passage of a card.

3. A card displaying apparatus comprising in combination, a casing provided with at least one aperture for the display of cards therethrough, a pair of guides sloping downwardly from rear to front of said casing in such a position as to hold the front card in the guide in front of said aperture, a second pair of guides below said aperture and inclining downwardly from front to rear, means for elevating cards from said lower guide to said upper guide, escapement means for controlling the exit of cards from the top and bottom guides, and automatic means for operating said escapement 100 105 110 115 120 125 means, said escapement means comprising a pivoted lever, a pair of rods depending from said lever and pivoted thereto, escapement blocks fixed at the lower ends of said rods, said blocks having angular slots therethrough for holding said cards or permitting the same to pass along the guides according to the position of the blocks. 115

4. In a device of the class described, an escapement mechanism comprising a block having an angular slot therethrough, said slot being so arranged as to form a shoulder for holding cards and also a point on the opposite side of the slot from the shoulder for insertion between the end card and the remainder of the row of cards, and automatic means for operating said blocks to permit the passage of a card. 120

5. A card displaying apparatus comprising in combination, a casing provided with 130

an upper and a lower aperture, a pair of guides sloping downwardly from rear to front of said casing in the upper part thereof in such position as to hold the front 5 card in the guide in front of the top aperture, a second pair of guides in said casing inclining downwardly from front to rear and in such position as to hold the front card therein so as to be seen in said lower 10 aperture, means for elevating cards from said lower guide to said upper guide, escapement means for controlling the exit of cards from said top and bottom guides, automatic means for operating said escapement means, 15 said escapement means comprising a pivoted lever, a pair of rods depending from said lever and pivoted thereto, escapement blocks fixed at the lower ends of said rods, said blocks having angular slots therethrough for 20 holding a card or permitting the same to pass along the guides according to the positions of the blocks.

6. A card displaying apparatus comprising in combination, a casing provided with 25 an upper and a lower aperture, a pair of guides sloping downwardly from rear to front of said casing in the upper part thereof in such position as to hold the front card in the guide in front of the top aperture, a second pair of guides in said casing inclining downwardly from front to rear and in such position as to hold the front card therein so as to be seen in said lower aperture, means for elevating cards from said lower guide to said upper guide, escapement means for controlling the exit of cards from said top and bottom guides, and automatic means for operating said escapement means, 30 said escapement means comprising a pivoted lever, a pair of rods depending from said lever and pivoted thereto, escapement blocks fixed to the lower ends of said rods, said blocks having angular slots therethrough for holding a card or permitting the same to pass along the guides according to the positions of the blocks, spring means for holding 35 said escapement means in position to prevent passage of a card on the guides, and an arm connected to said lever and projecting over into the path of a card which is being elevated from the lower guide to the upper guide for throwing the escapement blocks into position to permit the passage of 40 a card.

45 the same to pass along the guides according to the positions of the blocks, and spring

means for holding said escapement means in position to prevent passage of a card on the guides.

7. A card displaying apparatus comprising in combination, a casing provided with an upper and a lower aperture, a pair of guides sloping downwardly from rear to front of said casing in the upper part thereof in such position as to hold the front card 50 in the guide in front of the top aperture, a second pair of guides in said casing inclining downwardly from front to rear and in such position as to hold the front card therein so as to be seen in said lower aperture, 55 means for elevating cards from said lower guide to said upper guide, escapement means for controlling the exit of cards from said top and bottom guides, and automatic means for operating said escapement means, 60 said escapement means comprising a pivoted lever, a pair of rods depending from said lever and pivoted thereto, escapement blocks fixed to the lower ends of said rods, said blocks having angular slots therethrough 65 for holding a card or permitting the same to pass along the guides according to the positions of the blocks, spring means for holding said escapement means in position to prevent passage of a card on the guides, and 70 an arm connected to said lever and projecting over into the path of a card which is being elevated from the lower guide to the upper guide for throwing the escapement blocks into position to permit the passage of 75 a card.

8. In a device of the class described, an escapement mechanism comprising a block having an oblique slot cut across one face thereof, and automatic means for operating 80 said block to permit the passage of a card.

In testimony whereof I affix my signature in the presence of two witnesses.

DAVID W. BARROW.
